UNITED STATES PATENT OFFICE.

JOSHUA F. TANNATT, OF SPRINGFIELD, MASSACHUSETTS.

DESIGN FOR A STATIONERY-CASE.

SPECIFICATION forming part of Design No. 14,994, dated May 6, 1884.

Application filed March 10, 1884. Term of patent 14 years.

To all whom it may concern:

Be it known that I, JOSHUA F. TANNATT, of Springfield, in the county of Hampden and State of Massachusetts, have invented and produced a new and original Design for Stationery-Cases, of which the following is a full, clear, and exact description.

This design relates to cases for holding various articles of stationery; and it consists in the configuration of the case, as shown in the accompanying drawings, which form part of this specification.

Figure 1 represents a view in perspective of a stationery-case having my new design, said case being shown closed; and Fig. 2, a front view of the case open.

The body A of the case is of an oblong rectangular form on its face, with an opening, b, of V-like shape extending down the front of said face from its top to near its bottom, or-

namented externally by panels c c, having raised borders d d down the sides and lower end of the face of the case and sides of the opening b. The flap B of the case is also of V-like shape, corresponding with the opening b, but crossed at its butt or larger end by a rectangular-shaped piece or band, e. As shown in Fig. 2, opening b and flap B represent the figure of a diamond, with a band-like interruption where said figure is broadest. 25 30

I claim—

The within-described design for a stationery-case, consisting of a body, A, of rectangular marginal contour, V-like opening b, side panels, c c, having raised borders d d, and a V-like flap, B, and a band, e, as shown. 35

JOSHUA F. TANNATT.
